UNITED STATES PATENT OFFICE.

FRED B. COREY, OF SCHENECTADY, NEW YORK, ASSIGNOR TO GENERAL ELECTRIC COMPANY, A CORPORATION OF NEW YORK.

TIME-LIMIT CIRCUIT-CLOSER.

1,001,932.

Specification of Letters Patent. Patented Aug. 29, 1911.

Application filed March 5, 1909. Serial No. 481,471.

To all whom it may concern:

Be it known that I, FRED B. COREY, a citizen of the United States, residing at Schenectady, county of Schenectady, State of 5 New York, have invented certain new and useful Improvements in Time-Limit Circuit-Closers, of which the following is a specification.

My invention relates to time-limit circuit-10 closers, and is particularly applicable to electric interlocking machines.

In the electric control of railway switches and signals, it is frequently desirable that a certain time-interval should be fixed between 15 the successive closing of certain circuits.

The object of my invention is to provide a simple time-limit circuit-closer for the purpose of fixing such an interval.

20 My invention consists in providing a pivotally-mounted receptacle, containing a conducting fluid, divided into two chambers by a partition which has a restricted opening through which the conducting fluid flows 25 when the device is moved from one position to another, and placing in the chamber into which the fluid flows a plurality of independent sets of contacts so arranged that the fluid connects the contacts of each set successively, without connecting together 30 the different sets. This is accomplished by arranging the chamber with a plurality of branches in which the independent sets of contacts are placed.

35 My invention will best be understood by reference to the accompanying drawings, in which—

Figure 1 shows in cross section a time-limit circuit-closer arranged in accordance 40 with my invention, and Fig. 2 shows the circuit-closer applied to a well known form of lever lock.

In Fig. 1, A represents an inclosing casing in which is mounted the receptacle B, 45 which is composed of glass or other suitable insulating material. The receptacle B may conveniently be mounted in the casing A by filling the casing with cement and embedding the receptacle in it, as is indicated 50 in the drawing.

C represents a partition which divides the receptacle into two chambers. This partition is provided with a large opening D and at least one restricted opening d. One 55 of the chambers is provided with two

branches, in the larger of which are placed a pair of contact terminals E, and in the smaller of which are placed a pair of contact terminals F. A third pair of contact terminals G may be placed in the other 60 chamber.

When the device is rotated half a revolution from the position shown in Fig. 1, all the mercury runs through the large opening D in the partition C into the chamber 65 containing the contacts G, and connects these contacts together. When the device is returned to the position shown in Fig. 1, the mercury can flow back only through the restricted opening or openings d. The smaller 70 branch containing the contact terminals F is so arranged with respect to the opening or openings d that no mercury can flow into this branch until the other branch is 75 filled. There is, thus, a certain time-interval between the breaking of contact at the terminals G and the closing of contact between the terminals E, due to the time required for filling the larger branch of the lower chamber up to the terminals E, and 80 there is a further time-interval between the closing of contact at terminals E and the closing of contact at terminals F, due to the time required for the mercury to fill up the rest of the larger branch and then to overflow into the smaller branch so as to connect the contact terminals F together. Since 85 the amount of mercury is not sufficient to fill both branches, the contacts E and F are not connected together, although the 90 contacts of each set are connected together by the mercury.

In Fig. 2, the casing A is shown mounted on the shaft of the rotary switch H of a well known form of lever lock. This switch 95 is actuated by a connecting rod I, which is operated in the usual manner by the latch on the lever of an interlocking machine (not shown). J represents the lock magnet, the armature of which is carried by a latch K, which is normally held by a spring k in engagement with a notch in the cam K¹, but which, when the magnet J is energized, is lifted from the notch so as to leave the switch H free to turn. Collector 100 rings L may be placed on the shaft of the switch H for carrying current to the contact terminals within the casing A. 105

I do not desire to limit myself to the particular construction and arrangement of 110

parts here shown, but aim in the appended claims to cover all modifications which are within the scope of my invention.

What I claim as new, and desire to secure by Letters Patent, of the United States, is,—

1. A time-limit circuit-closer comprising a pivotally mounted receptacle, a conducting fluid therein, a partition dividing the receptacle into two chambers and provided with a large opening and a restricted opening through which respectively the fluid flows from one chamber to the other when said receptacle is moved, one of said chambers having a plurality of branches, one branch being located to receive the flow direct from the openings, and a plurality of independent sets of contact terminals in said branches adapted to be connected successively by the flow of fluid into said chamber.

2. A time-limit circuit-closer comprising a pivotally-mounted receptacle, a conducting fluid therein, a partition dividing the receptacle into two chambers and provided with a restricted opening through which the fluid flows when the receptacle is moved from one position to another, one of said chambers having two branches so arranged with respect to said opening that the fluid can enter one branch only after filling the other and the amount of fluid being insufficient to fill both branches, and a set of contact terminals in each branch adapted to be connected by the fluid. 25 30 35

In witness whereof, I have hereunto set my hand this 2nd day of March, 1909.

FRED B. COREY.
